UNITED STATES PATENT OFFICE.

ARTHUR R. BULLOCK, OF LAKewood, OHIO.

ROAD CONSTRUCTION.

1,367,236.

Specification of Letters Patent.

Patented Feb. 1, 1921.

Application filed October 13, 1919. Serial No. 330,183.

To all whom it may concern:

Be it known that I, ARTHUR R. BULLOCK, a citizen of the United States, residing at Lakewood, in the county of Cuyahoga and 5 State of Ohio, have invented certain new and useful Improvements in Road Construction, of which the following is a full, clear, and exact description.

The present invention relates to a construction which is adapted to be employed as a road or highway construction, particularly interurban highways or country roads.

The object of the invention is to provide a road construction having portions thereof which usually receive vehicle travel, constructed in such a fashion as to be highly resistant to wear and abrasion incident to travel of vehicles on the road and also to provide a construction wherein the road 15 provides a surface for vehicle travel which to a large measure prevents the sliding or skidding of vehicles, and furthermore, provides a construction which may be laid at 20 much less cost than concrete or brick roads as at the present constructed.

The present invention relates to the same general subject matter as that disclosed in my co-pending application Serial No. 311,372 but in the present invention the same 30 general results may be obtained by a construction which may be provided at much less cost.

Reference should be had to the accompanying drawings forming a part of this 35 specification in which Figure 1 is a top plan view of a road embodying my invention; Fig. 2 is a section of Fig. 1; Fig. 3 is a top plan view of certain elements in the road construction; Fig. 4 is a perspective 40 view showing a segment used in the road construction; Fig. 5 is a side elevation of a segment; Fig. 6 is a transverse section showing a segment embedded in concrete.

Concrete and brick roads as at present 45 constructed provide a continuous surface over which vehicles may travel and in my prior application before mentioned, the roadway there disclosed also provides a continuous surface.

50 This surface may be of sufficient width so as only to accommodate a single vehicle or it may be of such width as to accommodate two vehicles abreast.

In the present instance the roadway may 55 be constructed so as to fulfil either or both the conditions.

The road vehicles as at present constructed have their ground engaging wheels spaced a certain distance apart and these vehicles when passing over a road usually pretty 60 closely follow a given direction of travel inasmuch as the rule of the road is that vehicles shall keep to the right, therefore it is my conception that there is no necessity of constructing a road such as a concrete or 65 brick road with a continuing top surface but it is only necessary to provide as it were parallel tracks of sufficient width to accommodate vehicles of whatever wheel gage and to fill in the space between what I term the 70 track portions with dirt, sand, gravel or cinders.

Referring to the drawings, we may consider 1 as representing a highway, the top surface of which is composed of dirt, cinders or other material. Extending along the highway, and in spaced relationship are two continuing strips of concrete or similar material such as indicated at 2. These strips are spaced apart a given distance and this 80 spaced relation continues throughout their length.

The strips 2 are of sufficient width so that the wheels of vehicles having different gages may conveniently be accommodated upon the 85 strips 2.

The strips may be most conveniently formed of concrete and in laying the strips, suitable parallel trenches may be provided in the surface of the road and a body of 90 concrete laid in these trenches.

The depth of the body of concrete will be such as to give the body a firm anchorage in the road bed.

Embedded in the concrete are a series of 95 metallic plates which adjoin each other end on end and in alinement. These metallic bodies being indicated at 3 and they extend coincident with the length of the strips 2.

These metallic bodies 3 are embedded in 100 the concrete and adjacent the upper surface of the concrete so that the travel of the wheels of vehicles passing over the road will be upon these metallic plates, thus the wear comes upon these plates and not directly 105 upon the concrete.

The plates 3 may very readily be constructed in such a manner as to provide what I term an anti-skid surface. That is to say, they may be so fashioned as to substantially 110 prevent the slipping of vehicle wheel tires as they pass over the road.

In the present instance I provide a series of segments which are interlocked one with the other in such fashion that the segments form in effect a continuous body embedded 5 in the concrete strips thereby forming not only a reinforcing element for the concrete, but due to their interlocking action, form a continuous metallic body in themselves so that stresses and strains set up in the plates 10 by vehicles passing over the same are transmitted from one segment to the other.

One of the segments used is shown in perspective in Fig. 4 and is there shown comprising a casting which is formed with a 15 flange 4 along one edge thereof and a central rib 5 with slanting ribs 6 which join the central rib with the side of the segment upon which the flange 4 is located. Each segment adjacent the apex or the part where the ribs 20 6 converge is formed with recesses 7 and 8 and adjacent the widest portion of the segment lugs 9 and 10 are provided.

Each segment is provided with oppositely disposed openings 11 and 12 as shown in 25 Fig. 4.

The segments are substantially alike and are arranged so as to dovetail with each other as shown in Fig. 3 in which the projections 9 and 10 of each segment coöperate 30 with the openings 7 and 8 of adjacent segments.

It should be noted however, that the segments having the rib 4 are those segments which have their base portions toward each 35 other, while the wide portions of the segments which extend toward the outside of the road are not so provided with segments. A segment such as described without the flange or rib 4 is indicated at 13 in Fig. 3.

40 When the segments are arranged as shown in Fig. 3 the openings 11 and 12 in any given segment are oppositely disposed with respect to a similar opening in an adjacent segment and for the purpose of securing the 45 segments together I utilize a link such as indicated at 14 which is of sufficient length to extend through the openings formed in the adjacent segments. The link is secured in place by inserting pins 15 and 16 through 50 the link and bearing against an inside of the rib through which the opening that receives the link is formed. These pins are of such size as when driven in, that they will exert a wedging action and in accordance with 55 the degree of wedging action exerted they will join the segments more or less rigidly together.

From the foregoing it will be seen that the interlocking action between the segments is 60 secured through the projections upon the segments coöperating with the recesses in adjacent segments and by the joining of the segments through the links 14.

These segments are embedded in the concrete 65 so that the top surface of the segments

is substantially flush with the top surface of the concrete of the strips 2.

The ribs 6 are spaced apart thereby providing spaces between the same which spaces are filled by the concrete when the segments 70 are embedded therein.

As will be seen from the drawing the ribs 6 of each segment extend in a diagonal direction with respect to the long axis of the segment thereby forming a surface 75 which tends to prevent side slipping of a vehicle wheel which is passing over the same.

When the strips of concrete 2 with their embedded segments are laid in a roadway, 80 the space between the strips may be filled with dirt, cinders or other material, so as to form a substantially flush road surface.

The segments with the ribs 4 are provided for the purpose of providing a rib or ridge 85 which if engaged by the wheel of a vehicle passing along the strips, tends to prevent the wheel of the vehicle from leaving the strip. In other words it acts as a flange on a trackway to assist in guiding the wheels of 90 the vehicle if perchance the wheels of the vehicle should tend to ride off of the strips which form the runway or trackway of the road.

In the drawings I have shown a road construction which permits two vehicles to pass abreast thereby providing a trackway for travel in both directions. It should, however, be understood that this is not essential 95 as a single pair of concrete strips may be 100 used in which event vehicles will pass each other by one of the vehicles turning out and into the dirt road.

The construction which has been described may be laid at a comparatively low 105 cost and it is entirely possible to use for the purpose a cheaper concrete mixture containing sufficient cement to form rigidity and strength to hold the metal segments, but it does not need to be of the customary rich 110 dense concrete as ordinarily used in road construction in an attempt to provide a surface which will withstand the wear and tear 115 incident to vehicles passing over the same.

As shown in the right hand portion of 115 Fig. 2, I may use a tierod, such as indicated at 19, which will extend between the adjacent strips of concrete, the opposite end portions of the bars or tierods being embedded in the concrete so that the tierod 120 forms a spacing and retaining element between the strips of concrete to prevent spreading or relative movement between the strips of concrete.

These tierods, such as indicated at 19, may 125 be positioned at frequent intervals throughout the extent of the strips.

As shown at the left hand side of Fig. 2, the tierod instead of being directly embedded in the concrete, may be secured 130

through short lugs, such as indicated at 20 formed on the under sides of certain of the metallic members which are embedded in the concrete. The rods are secured to the 5 projections 20, and therefore portions of the rod are embedded in the concrete. The purpose and function of the rods just described are the same as that previously described.

The segments with the ribs 4 are provided 10 for the purpose of providing a rib or ridge which if engaged by the wheel of a vehicle passing along the strips, tends to prevent the wheel of the vehicle from leaving the strip. In other words it acts as a flange 15 on a trackway to assist in guiding the wheels of the vehicle if perchance the wheels of the vehicle should tend to ride off of the strips which form the runway or trackway of the road.

20 In the drawings I have shown a road construction which permits two vehicles to pass abreast thereby providing a trackway for travel in both directions. It should, however, be understood that this is not essential as a single pair of concrete strips 25 may be used in which event vehicles will pass each other by one of the vehicles turning out and into the dirt road.

The construction which has been described 30 may be laid at a comparatively low cost and it is entirely possible to use for the purpose a cheaper concrete mixture containing sufficient cement to form rigidity and strength to hold the metal segments, 35 but it does not need to be of the customary rich dense concrete as ordinarily used in road construction in an attempt to provide a surface which will withstand the wear and tear incident to vehicles passing over the same.

40 Attention is drawn to the fact that the segments are so constructed as to be overlapping with respect to each other so that a vehicle wheel in passing over the segments 45 makes contact with a succeeding segment before each has entirely left contact with a preceding segment. This obviates the de-

velopment of bumps in the road which might be the case in the event that the ribs passed transversely instead of diagonally. 50

While I have described the road construction as a straight road construction, it will be apparent that the general construction employed is applicable to curves in the road by simply modifying the shape of the segment to accommodate the curve where the curve is sufficiently sharp.

Where the curve in the road is but a gradual curve, such as the usual windings of the road, there is sufficient flexibility in the connection between the adjacent segments to accommodate such curves.

Having described my invention, I claim—

1. A roadway comprising parallel strips of concrete lying substantially flush with the 65 road surface and alined members embedded in each of the strips of concrete, said members being connected with each other to permit a limited amount of flexibility.

2. A roadway comprising parallel spaced 70 concrete strips, alined members embedded in each of said strips, each of said members having its top surface formed with diagonal ribs which ribs are embedded in the said 75 concrete and means connecting the said members which permits a limited amount of flexibility.

3. A roadway comprising parallel spaced concrete strips, alined members embedded in each of said strips, each of said members 80 having its top surface formed with diagonal ribs which ribs are embedded in said concrete.

4. A roadway comprising parallel concrete strips, alined members embedded in 85 each of said strips, each of said members being formed with extensions and depressions, the extensions engaging in depressions of adjacent members and means by which the said members are articulated together. 90

In testimony whereof, I hereunto affix my signature.

ARTHUR R. BULLOCK.
